UNITED STATES PATENT OFFICE.

THEODOR BRUNO PÜTTMANN AND MAX OTTO CLAUS, OF LEIPSIC-GOHLIS,
GERMANY.

MECHANICAL MUSICAL INSTRUMENT.

SPECIFICATION forming part of Letters Patent No. 563,800, dated July 14, 1896.

Application filed October 10, 1895. Serial No. 565,305. (No model.)

To all whom it may concern:

Be it known that we, THEODOR BRUNO PÜTTMANN and MAX OTTO CLAUS, subjects of the King of Saxony, residing at Leipsic-
5 Gohlis, Saxony, Germany, have invented cer-
tain new and useful Improvements in Me-
chanical Musical Instruments, of which the
following is a specification.

This invention relates to a mechanical mu-
10 sical instrument in which the strings are set
in vibration by the action of pressers hung
upon springs and adapted to fly back more
quickly than the strings which they have de-
flected, these pressers being operated by tap-
15 pet-wheels, which also govern and operate
the dampers by bringing the latter laterally
against the respective strings.

In the annexed drawings, Figure 1 is a lon-
20 gitudinal section through such musical in-
strument parallel with the strings and show-
ing one of the strings with its presser, tappet-
wheel, and damper, and a section of the mu-
sic-sheet, the parts being in the position in
25 which the damper is in action and the presser
in its resting position. Fig. 2 is a similar sec-
tion showing the position of the parts in which
the presser, here shown in a modified con-
struction, is pressed down and deflects the
30 string, while the damper is free and assumes
its position of rest away from the string.
Fig. 3 shows the damper separate from the
other parts, and Fig. 4 is an end elevation of
the same as seen from the right in Fig. 3.

S is the string; N, the music-sheet; R, the
35 rotary tappet-wheel; A, the presser, and D
the damper. The tappet-wheel is adapted to
revolve on the shaft R', which affords also a
bearing for the damper D, which has a hole
D' for passage of the shaft R', and lugs D²D²
40 to embrace the frame-bar F to prevent the
damper from revolving.

A is the presser, which may be made in one
piece with its spring-shank A', as in Fig. 1,
or may be a separate part, for instance, piv-
45 oted at X, as in Fig. 2, and held from the
string by a spring A', equivalent to the said
shank.

The damper D is slit at e to increase the
resiliency and elasticity of that part which
comes against the string. Such part is bent 50
at a, Fig. 4, to pass over the string and down
alongside the latter, and it is provided with
the boss b, projecting from its side in the path
of the teeth or tappets of wheel R, so that as
each tooth passes in front of and presses aside 55
this boss the damper is brought against the
string.

When a projection on the music-sheet N
strikes the uppermost tooth of wheel R, it
causes the wheel to be partially revolved. 60
This action first brings the damper into ac-
tion, as just described, and shown in Fig. 1.
As the movement continues, another tooth Z²
of the wheel presses down the presser A onto
the string, deflecting the latter, as shown in 65
Fig. 2, while the damper is released by the
tooth Z' passing over the boss b out of contact
therewith. When the tooth Z² has passed
over the end of the presser A, the latter
springs up, and its spring A' being shorter 70
than the string has a quicker movement than
the latter, so that the presser A leaves the
string, which is free to vibrate.

We claim as our invention—

In a mechanical musical stringed instru-
75 ment the combination of a stretched string
a presser therefor, a spring shorter than said
string supporting said presser therefrom, a
rotary tappet-wheel R adapted to bring the
presser against the string and a damper mov-
80 able laterally by said tappet-wheel, the said
damper being adapted to stand clear of said
string and having a boss b whereby the pas-
sage of a tooth of said tappet-wheel may de-
flect the damper in contact with the string. 85

In testimony whereof we have signed our
names to this specification in the presence of
two subscribing witnesses.

THEODOR BRUNO PÜTTMANN,
MAX OTTO CLAUS.
